UNITED STATES PATENT OFFICE.

HANS HOLZWARTH, OF MILWAUKEE, WISCONSIN.

ROTARY COMBUSTION-ENGINE.

SPECIFICATION forming part of Letters Patent No. 783,434, dated February 28, 1905.

Application filed September 28, 1903. Serial No. 174,906.

To all whom it may concern:

Be it known that I, HANS HOLZWARTH, a citizen of Germany, residing at Milwaukee, county of Milwaukee, and State of Wisconsin, have invented new and useful Improvements in Rotary Combustion-Engines, of which the following is a specification.

My invention relates to internal-combustion engines.

10 The object of my invention is to provide means for the practical application of the direct force developed by combustion in the operation of a turbine.

15 In an ordinary turbine no means are provided for compressing combustible gases nor for confining such gases during ignition even though a preliminary compression were provided for.

20 My invention therefore contemplates the provision of separate expansible combustion-chambers in which a compression may be secured (at least a final compression) and which will offer sufficient resistance to the initial pressure of the burning gases to produce a 25 complete ignition and then deliver the gases into the turbine in a manner to develop the highest efficiency.

25 My invention also contemplates utilizing the force expended in expanding one combustion-chamber to produce a final compression in another similar chamber, the arrangement being such that a four-cycle movement is secured by successive ignitions in a set of four chambers without reference to the movement of the turbine and entirely independent thereof.

In the following description reference is had to the accompanying drawings, in which—

30 Figure 1 is a side view of my invention, drawn partly in central vertical section. Fig. 2 is an end elevation showing the inlet end with the valve-actuating connections omitted and the connecting-ducts and supply-chambers shown diagrammatically. Fig. 3 is a detail plan view of a cylinder-head and the valve-actuating levers and valves. Fig. 4 is a detail front elevation of the valve-actuating connections.

35 Like parts are identified by the same reference characters throughout the several views.

The stationary member 1 of the turbine is provided with a head-plate 2 at the inlet end, on which are mounted a set of compression-chambers 3, 4, 5, and 6. These chambers are illustrated as cylinders provided with pistons 55 8, having connecting-rods 9 attached to an oscillating ring 10, mounted on a hub 11, which projects from the head-plate 2 and through which the turbine-shaft 12 extends. The connecting-rods 9 extend tangentially to the ring 60 10, whereby the movement of any piston is communicated to oscillate the ring, and thereby actuate the other pistons correspondingly. The compression-chambers are, however, arranged in pairs, with those of one pair at right 65 angles to those of the other pair, and the connecting-rods of each pair are attached to the ring on opposite sides, as shown in Fig. 2, whereby an outward movement of one piston will communicate a similar movement to one 70 piston of the other pair and an inward movement to one piston of each pair. Each chamber is provided with a gas-inlet valve 15, an air-inlet valve 16, and an igniter 17 of any ordinary type, also with an outlet-port 20, which 75 leads through the head-plate 2 and constitutes a nozzle for the discharge of the gases of combustion against the initial set of vanes 21 of the turbine. These ports 20 are normally closed by the pistons, but are opened when 80 the piston is substantially at the limit of its outward stroke. The chambers are charged from any suitable source of supply, represented in the drawings by a tank 23, pipes 24, and branch pipes 25 for gas and a tank 27, 85 pipes 28, and branch pipes 29 for air.

Valves 31 control the admission of water under pressure to the compression-chambers through suitable ducts 32, communicating with a suitable source of supply. The valve 31 of 90 any chamber is opened during the next return stroke of the piston after a charge has been fired, and the water is preferably admitted in the form of a spray to cool the cylinder and aid in the expulsion of the products of combustion, which are driven by the returning piston through a duct 34, which communicates with a chamber 35 in the low-pressure portion of the turbine. Valves 36 control the discharge of gases into the ducts 34.

The turbine may be of any ordinary type, except that the initial vane-supporting disks A B are of large diameter and the nozzles A' B' are formed for a rapid conversion of the 5 energy of the gases, which then enter the annular chamber 35 at a comparatively low pressure and are delivered at a less radius through the nozzles C' to the vanes C. The remaining 10 series of nozzles and vanes may be substantially the same in arrangement and construction as in any ordinary turbine.

The several compression-chambers are charged and fired in alternation, the outward 15 movement of a piston driven by a fired charge being communicated to expel the products of combustion in one of the other chambers, draw in a fresh charge in another chamber, and compress a fresh charge in another. A complete 20 four-cycle movement of each piston is thus provided for in correspondence with successive explosions in the respective chambers, the initial force of each charge when fired being utilized to operate the pistons and the remainder to operate the turbine. The compression 25 of a charge in one chamber provides an elastic cushion, which relieves the shock on the piston directly driven by the charge.

The valves 15 and 16, 31 and 36 are each 30 normally closed by springs 40. Cam-shafts 41 and 42, connected by bevel-gearing 43, are driven from the turbine-shaft by a worm-gear 44 and worm-wheel 45. These shafts are provided with sets of cams 47, one for each valve, and motion is communicated from each cam 35 to its corresponding valve through a suitable push-rod 49, valve-actuating lever 50, and valve-stem 51. The cams are positioned upon the shafts to open the valves at the proper intervals. The push-rods 49 for operating the 40 gas-valves 15 and those for operating the water-valves 31 are mounted in bearings 54 and are resiliently supported by springs 55. A governor 56 of ordinary construction is used to control the supply of gas and water to the 45 compression-chamber through the medium of the rod 58, bell-crank 59, bar 61, valve-levers 62 and 63, and valves at 64 and 65, controlling the flow of gas and water through the pipes 24 and 32, respectively.

50 In operation, assuming that the chamber 3 is charged and fired, the expansion of the burning gases pushes the piston outwardly and communicates motion through the ring and connecting-rods to move the piston of chamber 5 outwardly and draw in a charge of gas and air through the admission-valves of that chamber. Simultaneously the piston of chamber 4 moves inwardly to compress a charge therein, all the valves of this chamber 55 being closed. The piston of chamber 6 is also moved inwardly to expel the residue of the preceding charge and the steam produced by the incoming water, the valves 31 and 36 of this chamber being open and the contents of 60 the chamber being driven forcibly into the

turbine at 35 and its remaining energy utilized. When the piston of chamber 3 reaches the limit of its stroke, the expanding gases are delivered into the turbine, and the charge in chamber 4 being then fired an opposite 70 movement of the pistons and ring is produced in which the residual gases are expelled from chamber 3 through the valve 36 and a fresh charge drawn into chamber 7 with compression in chamber 5. 75

In the drawings I have shown the various parts of the turbine provided with water cavities or passages 60. These are preferably supplied or provided with a circulating current from the water-duct 32. These passages 80 may be varied in form and location as desired.

Having thus described my invention, what I claim as new, and desire to secure by Letters Patent, is—

1. The combination with a turbine; of a plurality of cylinders having discharge-ports arranged to constitute initial nozzles for the turbine; pistons in said cylinders; an oscillatory element; connections between said element 90 and the respective pistons; means, controlled by the turbine, for admitting and igniting combustible charges in the several cylinders in succession; and means for opening said discharge-ports during the forward movement of 95 the piston under pressure of the ignited charge.

2. The combination with a turbine; of a series of compression-chambers having nozzle-ports communicating with the turbine at its inlet end; a piston in each of said chambers; and connections between the pistons of the respective chambers; said connections being arranged to transmit similar motion from one piston to another and a reverse motion to two 100 of the other pistons; means for admitting combustible charges to the respective chambers successively and igniting such charges; a valved passage leading from each chamber to the low-pressure portion of the turbine intermediate of the inlet and discharge ends; and means for opening said passage during the 105 next return movement of the piston after the ignition of the charge in such chamber. 110

3. The combination with a turbine, of a device mounted to oscillate loosely on a suitable support at the inlet end of the turbine; a set of expansion-chambers each having a movable element connected with said oscillatory device; means for introducing combustible charges 115 into said expansion-chambers; means for igniting such charges in succession; and means for delivering the gases of combustion from each chamber to the turbine after actuating said movable element. 120

4. The combination with a turbine, of a device mounted to oscillate loosely on a suitable support at the inlet end of the turbine; a set of expansion-chambers each having a movable element connected with said oscillatory device; 125

means for introducing combustible charges into said expansion-chambers; means for igniting such charges in succession; and means for delivering the gases of combustion from each chamber to the turbine after actuating said movable element; said oscillatory device and the movable elements of the several expansion-chambers being arranged to transmit the force of expansion in one chamber to compress 5 the gases in another chamber.

5. The combination with a turbine having a plurality of running wheels; of a set of expansion-chambers provided with means for compression and ignition of explosive charges;

10 means for delivering the gases of combustion from said chambers to the initial running wheel of the turbine during the period of combustion of such gases; and means for delivering the residual gases to other running wheels of the turbine.

15 6. In an internal - combustion engine, the combination of a turbine; a compression-chamber having a normally closed port leading to the initial set of vanes in the turbine; and another 20 normally closed port leading directly to the low-pressure portion of the turbine; means for igniting charges in said chamber; and means for opening the first-mentioned port during the expansion of an ignited charge,

25 30 and opening said last-mentioned port for the 30 expusion of the residual products of combustion.

7. In an internal - combustion engine, the combination of a turbine; a compression-chamber having a normally closed port leading to the initial set of vanes in the turbine, and another normally closed port leading directly to the low-pressure portion of the turbine; means for igniting charges in said chamber; and

40 means for opening the first-mentioned port during the expansion of an ignited charge, and opening said last-mentioned port for the expusion of the residual products of combustion together with means for injecting water 45 into said chamber during the expusion of such residual products.

8. In an internal - combustion engine, the combination of a turbine; a compression-chamber having a normally closed port leading to the initial set of vanes in the turbine, and another normally closed port leading directly to the low-pressure portion of the turbine; means for igniting charges in said chamber; and means for opening the first-mentioned port during the expansion of an ignited charge, and opening said last-mentioned port for the expusion of the residual products of combustion; together with a governor in operative relation to the turbine; and connections therefor, adapted to regulate the admission of combustible charges.

9. In an internal-combustion engine, the combination of a turbine; a compression-chamber having a normally closed port leading to

the initial set of vanes in the turbine, and another normally closed port leading directly to the low-pressure portion of the turbine; means for igniting charges in said chamber; and means for opening the first-mentioned port during the expansion of an ignited charge, and opening said last-mentioned port for the expusion of the residual products of combustion; together with means for injecting water into said chamber during the expusion of such residual products; together with a governor in operative relation to the turbine, and connections therefor, adapted to regulate the admission of water and of combustible charges, to said chamber.

10. In an internal-combustion engine, the combination of a combustion-chamber; and a turbine having plurality of series of vanes and corresponding inlet - nozzles connected with said chamber; said turbine having the vanes of the initial series, at greater radial distances from the axis than those of succeeding series, and the initial nozzles constructed for a more rapid conversion of the energy of the gases than those pertaining to the vanes at the shorter radii.

11. The combination with a turbine, of a set of cylinders, located at the inlet end thereof; a piston in each cylinder connected with the pistons of each of the other cylinders and unconnected with power-transmitting devices of the turbine, each of said cylinders being provided with a port near each end communicating with the turbine; one of said ports being covered by the piston, except when the latter is near the limit of its outward movement; a valve for the other of said ports; means for introducing and igniting charges in said cylinders and means for opening said valve during the return stroke of the piston.

12. The combination with a turbine, of a set of cylinders, located at the inlet end thereof; a piston in each cylinder connected with the pistons of each of the other cylinders and unconnected with power-transmitting devices of the turbine; each of said cylinders being provided with a port near each end communicating with the turbine; one of said ports being covered by the piston, except when the latter is near the limit of its outward movement; a valve for the other of said ports; means for introducing and igniting charges in said cylinders and means for opening said valve during the return stroke of the piston, together with means for introducing a jet of water to each cylinder during the return stroke of its corresponding piston.

In testimony whereof I affix my signature in the presence of two witnesses.

HANS HOLZWARTH.
